[57] **ABSTRACT**

An electromagnetic fuel injection device for internal combustion engines comprising electric circuit so arranged that the number of cylinders which undergo simultaneous injection in one cycle of the engine is lessened at low rotational speeds where the control time of the amount of fuel injected is relatively long so as to operate all the fuel injection valves through several stages thereby the period of each fuel injection will not correspond to an overlapping period, while for high speed rotation the number of cylinders related to simultaneous injection is increased to equivalently extend said control time.

**ELECTROMAGNETIC FUEL INJECTION DEVICE
FOR INTERNAL COMBUSTION ENGINES**

This invention relates to an electromagnetic fuel injection device for multi-cylinder type internal combustion engines.

Heretofore, a fuel injection device of this type provided controlled fuel injection in an amount in accordance with the duration T of the voltage applied to an electromagnetic fuel injection valve. With the rise of engine rotation speed N , the controllable time of the engine t ($t = (60/N)$ sec) will be decreased. When the controllable time is reduced to a value smaller than the duration T of the voltage applied to the electromagnetic valve, control of the amount of fuel injected has been impossible. It is also known in the prior art that an engine equipped with this sort of device is constructed to perform all cylinder simultaneous fuel injection for each cylinder of four cycle multi-cylinder engine and that during the injection period in certain cylinders suction valves thereof are opened while their exhaust valves are insufficiently closed (valve overlap) so that the gas mixture is blown off wastefully. This effect was particularly apparent at the low speed rotation consequent on the bad fuel consumption rate. The present invention provides an electromagnetic fuel injection system for an internal combustion engine comprising a rotational speed to voltage converter circuit for producing voltage output pulses in accordance with the rotational speed of the engine, a mono-stable multivibrator circuit for receiving the pulses produced by the converter and producing an output in accordance therewith and a control circuit for controlling energization of a plurality of sets of control coils to thereby control actuation of a corresponding plurality of fuel injection valves. At low speed operation, the outputs of the multivibrator circuit and converter are connected to the control circuit so as to provide alternate energization of the sets of control coils and hence provide simultaneous minority-cylinder injection. A speed responsive switch suppresses the output pulses from the converter when the engine reaches a predetermined speed so as to provide simultaneous energization of the sets of coils and hence provides simultaneous majority-cylinder injection.

In order that the invention may be more clearly understood, reference will now be made to the accompanying drawings in which:

FIG. 1 is a graph showing the fuel requirement characteristics as a function of rotation speed of an internal combustion engine;

FIG. 2 is a block diagram showing a fuel injection device according to the invention;

FIG. 3 is an electrical circuit diagram of the fuel injection device;

FIG. 4 is a diagram showing pulse waveforms of potentials at various junctions of an injection amount correcting circuit;

FIGS. 5 and 6 are diagrams showing pulse waveforms at each part of the circuit, in each of which (i) represents a set of waveforms relating to simultaneous fuel injection for two cylinders, and (ii) represents a set of waveforms relating to simultaneous fuel injection for four cylinders; and

FIG. 7 is a graph showing a modification of the characteristics of the duration T of pulse.

Referring now to the schematic block diagram of FIG. 2, block A denotes a known rotation speed-voltage converting circuit for producing a voltage pulse related to the rotation speed of the engine. Block B denotes a known monostable multivibrator circuit which generates a rectangular pulse whose frequency varies with the rotation speed of the engine and whose pulse length changes with variations in the vacuum of the suction pipe of the engine. Block D designates an output amplifier circuit for controlling the fuel injection valves of the engine E. Block C designates an injection amount correcting circuit which corrects the fuel injection amount relative to the rotation speed of engine. The construction of these circuits is now shown in particulars in FIG. 3. In the figure, section A includes intermittent contacts S1, S2 of the engine, capacitors C1, C2, etc, and generates two pulse trains alternately produced by frequencies proportioned to the engine speed through alternate closing of the contacts S1 and S2. Section B includes a multivibrator circuit having transistors Tr1 and Tr2, and a timing element having transformer L and resistors R0 and R1. The iron core of transformer L moves in proportion to the vacuum of a suction pipe P of the engine and can change the inductance of a secondary coil of the transformer L so that the duration of the pulses produced varies with the variation in the vacuum of the suction pipe of the engine. Section C is formed of transistors Tr3 - Tr7, capacitor C3 - C7, resistors R3 - R5, variable resistors VR1 - VR6, diodes D1 - D3 and a rotation responsive switch S3, and is arranged to satisfy characteristics of fuel requirements. Section D is formed of transistors Tr8 - Tr11, control coils L1 - L4 of electromagnetic fuel injection valves divided into two groups each consisting of two coils and diodes D4 and D5.

Application of the device of the invention to a four cylinder engine is now illustrated in detail. In reference to FIG. 3, the rotation responsive switch S3 is opened during the low speed rotation (3,500 r.p.m. or less in an experimental engine). The base of the transistor Tr8 becomes negative only when the intermittent contact S1 of the rotation speed-voltage converter circuit is closed. The contact W of the monostable multivibrator circuit B is supplied with a negative trigger pulse through the circuit of the capacitor C1 and diode.

Accordingly, the base of transistor Tr1 becomes negative and non-conductive and the transistor Tr2 conductive. Current flows in the primary coil of the transformer L and a voltage is induced in the secondary coil. In consequence, current produced by the induced voltage flows in the resistor R1 causing a drop in the terminal voltage of the resistor R1 generated from a power source voltage and turns the base of the transistor Tr1 negative. The current of the induced voltage is exponentially reduced but it still maintains the base of the transistor Tr1 negative until the current drops below a predetermined value. Therefore, the transistor Tr2 is retained in conductive state and generates on a junction U1 a pulse T0 related to the induced voltage of the transformer L. In FIG. 4, the pulse T0 is shown at waveform U1. In the same figure, the ordinate denotes the amplitude and the abscissa denotes the time t .

Hence, the bases of the transistors Tr8 and Tr11 connected to the terminal U1 becomes negative through

the pulse T_0 . As the intermittent contact S_2 is opened the base of the transistor Tr_{11} is retained in positive. The base of the transistor Tr_8 turns negative and non-conducting and the transistor Tr_9 becomes conducting. The electromagnetic coils of the fuel injection valves L_1 and L_2 are excited and fuel is injected. On the other hand, the base of the transistor Tr_{11} is fed positive and negative pulses so that the base thereof becomes conducting.

Thus, the transistor Tr_{10} turns non-conducting. Therefore, the fuel injection valves L_3 and L_4 will not inject fuel. When the intermittent contact S_1 is opened and the contact S_2 is closed, then the trigger pulse passing through the capacitor C_2 and diode is fed to a junction W . Said pulse generates the pulse T_0 thereby providing a negative pulse to the bases of transistors Tr_9 and Tr_{11} . As the contact S_1 is opened the base of transistor Tr_8 turns positive and the transistor Tr_9 turns non-conducting. Therefore, the valves L_1 and L_2 will not inject fuel but the valves L_3 and L_4 will inject fuel. Accordingly, at a low speed rotation of the engine, each of the two cylinders undergo simultaneous injection alternately (hereinafter referred to as simultaneous injection for two cylinders).

In the subsequent high speed rotation of the engine, the rotation responsive switch S_3 is closed so that a positive pulse is supplied via intermittent contacts S_1 and S_2 to the fuel injection valves L_1 - L_4 and shortcircuited through diodes D_4 and D_5 . At the same time, the pulse from the intermittent contact S_2 passing through the capacitor C_2 will disappear. The pulse T_0 is generated only through the intermittent contact S_1 . Hence, assuming that the period of the pulse T_0 is t before shortcircuiting of S_3 this period becomes $2t$ after shortcircuiting. Thus the fuel injection valves L_1 - L_4 will make simultaneous injection by the pulse T_0 (hereinafter referred to as simultaneous injection in four cylinders). This is shown in FIG. 5, in which the ordinate denotes the pulse and the abscissa denotes the time, (i) shows simultaneous injection in two cylinders, and (ii) simultaneous injection in four cylinders. According to the invention, therefore, each two cylinders alternately undergo fuel injection at the low speed of the engine and each four cylinders simultaneous injection at the high speed of the engine. Furthermore, the period at the time of the four cylinder simultaneous injection is double the period of two cylinder simultaneous injection. There is caused no variation in the injection amount of fuel before and after switching over of the injection.

In accordance with the present invention, moreover, the correction of the fuel injection amount responsive to the engine r.p.m. is effectively performed. Generally, the air suction amount of the internal combustion engine initially increases with the rise of rotation speed due to resistance of the suction air pipe etc. and subsequently it decreases as has been well known. Thus it is required to vary the amount of fuel supply in conformity with this circumstance. The relation of the fuel supply and the rotation speed of engine is shown in FIG. 1, in which the ordinate shows an injection amount of and the abscissa shows the rotation speed N of the engine. The correction of the fuel injection amount is realized in the circuit of section C. The pulse T_0 generated in the collector of the transistor Tr_2 of

circuit B is also supplied to the fuel injection amount correcting circuit C. The transistor Tr_3 produces on junction U_2 a pulse T_1 which is shown in FIG. 4 at waveform U_2 as and is determined by the capacitor C_3 and the resistor R_3 . The transistor Tr_4 produces on junction U_3 a pulse T_2 which is shown in FIG. 4 at waveform U_3 and is determined by the capacitor C_4 and the variable resistors VR_1 and VR_2 .

The transistor Tr_5 produces on junction U_4 a pulse T_3 which is shown at waveform U_4 in FIG. 4 and is determined by the capacitor C_5 and the variable resistors VR_3, VR_4 . The transistor Tr_6 produces on point U_5 a pulse T_4 which is shown in FIG. 4 at waveform U_5 in an inverted form of the pulse T_3 . Under this condition, the transistor Tr_6 is in conducting state so that the capacitor C_6 is discharged with the discharge characteristics as determined by the variable resistor VR_5 . When the pulse T_4 disappears then the transistor Tr_6 becomes non-conducting and the capacitor C_7 is charged. The charging process is performed with the characteristics as determined by the variable resistor VR_6 . The pulse of the transistor T_2 is applied in the charge through the diode D_3 to make constant the initial condition of the discharge potential. Accordingly, the potential of the connection U_6 will vary as shown in FIG. 4 at waveform U_6 . In FIG. 4, the portion or part α of the waveform U_6 designates the discharge process of the capacitor C_6 and the portion or part β denotes the charge process thereof. This potential is amplified by the transistor Tr_7 and the amplified potential is supplied to a junction U_7 of secondary coil of the transformer L through the variable resistor VR_7 .

If the potential is high in the junction U_7 the time is shortened to retain the point W in the negative by the transformer L . The pulse length of the pulse T_0 will then become small, and if the potential is low the pulse length of the pulse T_0 becomes large. As the rotation speed of the engine is raised the pulses T_0 - T_4 move to the left as shown by dotted lines in FIG. 4. As the potential of the junction U_7 will vary as shown in the dotted waveform since the pulse T_2 is applied therein earlier. This pulse T_2 is supplied at point Z , corresponding to the engine r.p.m. No of FIG. 1, from part β of the low speed rotation area with the rise of speed and applied in part α in the high speed rotation area. Thus, the potential of the junction U_7 decreases by increase of rotation speed at the low speed rotation side and increases at the high speed rotation side with Z as a turning point as shown in FIG. 4. As the result, a voltage characteristic of a chevron-shape may be obtained as shown in FIG. 1.

As hereinbefore described, the injection period in the four cylinder simultaneous injection is double the period of the two cylinder simultaneous injection. If the charge and discharge circuit including the capacitor C_6 in the four cylinder simultaneous injection is same as in the two cylinder simultaneous injection, the position of point Z corresponding to the engine rotation speed No will be displaced. Since it is provided that the injection period is doubled, or the time abscissa is double the previous length, the time constant of the charge and discharge circuit is required to be doubled. This adjustment may be performed in the following way. Simultaneously as the switch S_3 is closed in response to the high speed rotation of the engine the negative sides of

the diodes D1 and D2 assume the positive potential. The discharge of each of the capacitors C4 and C5 through parallel circuits of VR1, VR2 and VR3, VR4 respectively is performed solely through the circuit of VR1, VR3 as the circuit of VR2, VR4 are opened. Therefore, the consequent discharge time becomes longer and the pulse length of the pulses T2, T3 is doubled. As the capacitor C7, which was formerly open circuited, is connected in parallel with the capacitor C6, and assuming that the capacitance of the capacitor C6 is equal to that of the capacitor C7, then the gradients of the portions α and β of the waveform U6 of FIG. 4 are respectively turned to half due to the consequent change in rise time. In FIG. 6, curves U1-U7 respectively represent voltage waveforms at various junctions, the ordinate denoting an amplitude and the abscissa denoting time. In the same figure, (i) shows simultaneous injection for two cylinders and (ii) simultaneous injection for four cylinders. As will be apparent from this figure, the period of each pulse in case (ii) is double that of each pulse of (i). The potentials $X\beta Z\alpha$ of the waveform U7 will have a gradient of $\frac{1}{2}$ characteristics as in $X1\beta1Z1\alpha1$. Thus the potential e at the termination of second pulse T0 affecting the multivibrator circuit B is common to both cases (i) and (ii). Even though the potential is changed over the pulse length of the second pulse T0 is not changed and accordingly the injection characteristics will not become non-continuous. Comparison of the potential e must be attempted at the high speed rotation side but now it has been made at the low speed rotation side for convenience of description.

Characteristics of the continued time T of applied voltage may be modified, as shown at dotted line *a* in FIG. 7, by adjusting the variable resistors VR1-VR4 to desirably define the pulse lengths of the pulses T2, T3, and adjusting the variable resistors VR5, VR6 to change the discharge time of the capacitor C6 and the curve $X\beta Y Z\alpha$ of the waveforms U6, U7 shown in FIG. 4.

It is apparent that another transistor circuit for generating pulses T5, T6 may be provided between the pulses T3 and T4 with the pulses T3 and T6 applied to the base of the added transistor to form an OR-circuit and change the discharge waveform of the capacitor thereby providing irregular characteristics thereto as shown in dotted curve *b* of FIG. 7. Change of the rotation speed of engine may be obtained by changing the turn of the throttle valve by the accelerator pedal to change the vacuum of the suction air pipe P, the induced voltage of the transformer L responsive to the vacuum, and the pulse length of the pulse T0, thereby adjusting the injection amount.

In accordance with, the invention, as described above, the device may be switched over to the four cylinder simultaneous injection at the high speed rotation of the engine at which the fuel injection amount may be fairly controlled. At the same time, the device will be switched over to the four cylinder injection and thereby period of injection may be doubled. As the result, there will not be produced any difference in the injection amount of fuel before and after switchover from the two cylinder to the four cylinder operation. The fuel amount adjusting means may have a characteristic as desired adapted for the engine so as to

elevate the consumption of fuel. The duration of the pulse in the switchover operation will not have discontinuity so that stable control may be obtained over the whole area of rotation speed of the engine.

It is of course to be noted that the switchover operation is not limited only to the two-to-four cylinder fuel injection but it may also be applied to the fuel injection in the ratio of 1:2.

While the invention has been described in detail with respect to a particular preferred embodiment of the invention it will be understood that various changes and modifications may be made without departing from the spirit and scope of the invention.

What is claimed is:

1. An electromagnetic fuel injection system for an internal combustion engine, comprising rotational speed to voltage converter means for producing voltage output pulses in accordance with the rotational speed of the engine, monostable multivibrator circuit means for receiving said pulses and producing an output in accordance therewith, control circuit means for controlling energization of a plurality of sets of control coils for controlling actuation of a corresponding plurality of fuel injection valves, means for connecting the output of said converter means and the output of said multivibrator circuit means to the input of said control circuit means so as to provide alternate energization of at least two sets of said sets of control coils and hence provide simultaneous minority-cylinder injection, and speed responsive switching means for suppressing output pulses from said converter means when the engine reaches a predetermined speed so as to provide simultaneous energization of said at least two sets of coils and hence provide simultaneous majority-cylinder injection, said system further comprising timing circuit means connected to the input of said control circuit means for controlling the fuel injection control voltage in accordance with the fuel supply versus rotational speed characteristic of the engine, said timing circuit including a discharge circuit and said speed responsive switching means including means for varying the discharge time of said discharge circuit when the engine reaches said predetermined speed, said timing circuit including a plurality of RC components for determining the time constant of said timing circuit and said speed responsive switching means including a switch means for switching selective ones of said RC components in and out of said timing circuit to control charging and discharging of said timing circuit so as to maintain the rotational speed-fuel injection characteristic of the system.

2. A system as claimed in claim 1 wherein the time constant of said timing circuit is doubled when the system switches from simultaneous minority-cylinder injection to simultaneous majority-cylinder injection.

3. A system as claimed in claim 1 wherein said control circuit means includes at least first and second switching transistors for controlling energization of said coils and said means for connecting the output of said converter means to said control circuit means comprises alternately operable switches for controlling the period during which said transistors conduct, said speed responsive switching means including a switch for, when actuated, substantially short-circuiting one of said alternately operable switches to thereby increase

the period during which at least one of said first and second switching transistors conducts.

4. A system as claimed in claim 1 wherein said monostable multivibrator circuit means includes means for varying the duration of the output pulses produced thereby in accordance with the suction forces exerted by the engine suction pipe.
